UNITED STATES PATENT OFFICE.

ANNA RUTH WHITE, OF LA CROSSE, WISCONSIN.

BUFFER.

1,158,350.

Specification of Letters Patent. Patented Oct. 26, 1915.

Application filed June 16, 1913. Serial No. 773,940.

To all whom it may concern:

Be it known that I, ANNA RUTH WHITE, a citizen of the United States, residing at La Crosse, in the county of La Crosse and State 5 of Wisconsin, have invented a new and useful Improvement in Buffers, of which the following is a specification.

The object of this invention is to provide a buffer which is adapted for use on articles 10 of furniture and especially upon corner posts of beds whereby they are prevented from scratching and marring baseboards and walls, and said posts are protected against damage.

15 This invention provides a simple and inexpensive device which may be adjusted to a post or other support for use and upon which the resilient buffer element can be easily and quickly renewed when worn, by 20 an inexperienced person.

In the accompanying drawing forming part of this specification, Figure 1 is a detail in perspective of a portion of a bedstead equipped with one style of my improved 25 buffer; Fig. 2 is a side view of my invention shown applied to a bed post, a detail of the latter being illustrated; Fig. 3 is a plan of the construction illustrated in Fig. 2; Fig. 4 is a plan of my invention when constructed 30 for use to protect a post and the walls in the corner of a room; Fig. 5 is a section of Fig. 4 on the line X—X and Fig. 6 is an enlarged perspective of a simple form of my invention detached from its support.

35 In the drawing A indicates a corner post of an article of furniture upon which my improved buffer B is adapted to be mounted, said post representing one of the corner upright elements of a bed or the leg or other 40 portion of any article of furniture which it is desired to protect from becoming marred and from abrading a wall or base board.

My improved buffer consists of a guard arm or extension 2 of any desired shape 45 upon which is adapted to be mounted a resilient buffer element 3, which projects laterally from the surface of the arm and is adapted to guard and protect the post A and protuberances thereof from coming into 50 contact with a laterally adjacent object such as a base board or wall to prevent abrading the surface thereof.

As illustrated the arm 2 is formed with a groove 4 in its vertical walls and the buffer 55 element consists of a band made of rubber or other resilient suitable material which is

stretched lengthwise around the arm in the groove 4 where it is held firmly in exposed position for use. The arm 2 is provided with a split collar 5 or other suitable means 60 for securing the arm on the post A in laterally extending position and in a plane vertically removed from that assumed by its securing means as shown in the drawing so as to facilitate renewal of the resilient material should its usefulness become impaired. A portion 6 of the collar 5 is formed integral with the arm and the other portion 7 is hinged to the arm at 8 as illustrated. These portions of the collar are adapted to 70 be clamped around the post by means of the bolt 9, the inner surface of the collar being protected by a strip of felt 10 or other suitable soft material which prevents the collar from abrading the surface of the post. The 75 extension arm 2 is offset vertically above the collar 5, so that the band 3 of resilient material may be made to encircle and clasp the arm. An ordinary rubber band may be used for the buffer surface.

When it is desired to provide a buffer surface which will project against two walls such as in the corner of a room, a pair of buffers such as C and D (see Fig. 4) may be employed. These buffer elements being 80 mounted upon a split collar or other suitable fastening means such as 11, which may be clamped around the corner post A by the use of the bolt 12. Each buffer element as illustrated consists of a frame or body 13 having a convex outer surface 14 and a grooved back surface 15. The buffer band 16 is stretched lengthwise around the surface 14, and in the groove on the back surface 15, said groove serving to hold the band vertically in position with the outer portion 17 thereof exposed on the front convex surface of the buffer and serving to protect the post A from coming into contact with a wall. The buffer elements are mounted in horizontal position at substantially 90 degrees to each other and each buffer element has its body 13 extensibly mounted in a grooved lug 18 integral with the collar 11 by means of the set screw 19 passing through the lug 105 and a slot 20 in the projection 21 on the body of the buffer element. In this manner the buffer element may be adjusted to vary the distance of its buffer surface from the post.

It is obvious that the feature of extensibility or adjustability as above described

- may be used when one or more buffer elements are employed. It is further obvious that the circumferential surface 17 on the buffer element may be extended or shortened 5 as desired and when increased sufficiently a single buffer element will project against two corner walls and thus made to take the place of two buffer elements as illustrated in Fig. 4.
- 10 A simple modification of my invention is illustrated in Fig. 6, in which E indicates the lateral buffer arm carried by the split collar F by which the buffer is adapted to be secured to a post. On the outer end of 15 the arm E is mounted a tip G made of rubber or other resilient material which is adapted to protect the post from coming into contact with a wall. The tip G is illustrated as being socketed in the end of the 20 arm E, where it is secured by glue or other suitable means. The collar F as illustrated is composed of an integral section 22 on the arm and a hinged section 23 and the extremities of said sections are clamped together by means of the bolt 24 carrying the 25 thumb nut 25 which is threaded thereon.
- In accordance with the patent statutes I have described the principles of operation 30 of my invention together with the apparatus which I now consider to represent the best embodiment thereof but I desire to have it understood that the construction shown is only illustrative and that the invention can be carried out by other means and applied 35 to uses other than those above set forth within the scope of the following claims.

Having described my invention, what I

claim as new and desire to protect by Letters Patent is:—

1. A buffer of the type described comprising pivoted sections for securing it to a support, one of said sections having an integral offset portion provided with an aperture, a guard arm having an elongated slot adjacent one end and terminating in an enlarged portion at its other end, a set-screw extending through the slot in said arm and the aperture in said offset for adjustably securing said arm with respect to said sections, and a resilient band secured about said enlarged portion as and for the purposes specified. 40
2. A buffer of the type described comprising pivoted sections for securing it to a support, one of said sections having an integral recessed offset portion provided with an aperture, an outwardly projecting guard arm adapted to slide within the recess of said offset portion, said arm having an elongated slot adjacent one end, a set-screw extending through the slot in said arm and the aperture in said offset for adjustably securing said arm with respect to said sections and support, and a resilient bumper carried by and extending beyond the free end of 55 said arm. 60

In testimony whereof, I have signed my name to this specification in the presence of the subscribing witnesses.

ANNA RUTH WHITE.
